UNITED STATES PATENT OFFICE.

LEE OTIS THOMPSON, OF VANCOUVER, WASHINGTON.

SEAT-POSITIONING DEVICE.

Application filed November 20, 1926. Serial No. 149,748.

My invention relates to seats as used in any and all public places wherein the same are arranged in rows and wherein it may be found desirable for the purposes of reaching or departing from the seat to transfer the seat from a point disposed away from the entrance aisle to a point adjacent the aisle.

The primary object of my invention consists in new, novel and useful means whereby 10 the seat to be occupied or to be released from occupancy may be transferred by simple and efficient means from a point away from an aisle location directly to an aisle location.

A further object of my device, consists in 15 providing selective, manipulative means for the bringing of this about, either by the occupant of the seat manipulating the selective, operative means, or by the same being manipulated or operated by the usher or other person in charge, from the aisle location.

A still further object of my device, consists in selectively transferring of seats from one row to another, or from one location to another, in certain and predetermined group 25 selections.

Formerly it was the common practice in public gathering places, and primarily in theatres, for the patrons of the place to be occupied to visit the place at stated intervals 20 and to depart therefrom at stated intervals, but in many gathering places at the present time this is not true and a new condition has arisen,—people are entering and leaving public places continuously over long periods, and 30 this has created a new condition so that it is now desirable for patrons to enter and depart from their seats at any time and to furnish adequate, simple and efficient means to accommodate patrons with the least annoyance to the other patrons, is the primary object and purpose of my invention.

With these and incidental objects in view, the invention consists in certain novel features of construction and combination of 45 parts, the essential elements of which are set forth in the appended claims, and a preferred form of embodiment of which is hereinafter shown with reference to the drawings which accompany and form a part of this specification.

In the drawings:—

Fig. 1 is a top plan view of two seat sections, having four seats disposed in each section.

Fig. 2 is a top plan view of the space to

be occupied by the seats, with the seats removed therefrom.

Fig. 3 is an inverted plan view of the operating mechanism for the seats illustrated in Fig. 1, and for the drives illustrated in Fig. 2. 60

Fig. 4 is a cross section view, taken on line 4—4 of Fig. 1, looking in the direction indicated.

Fig. 5 is a cross sectional view, taken on line 5—5 of Fig. 1, looking in the direction 65 indicated.

Fig. 6 is a side elevation, partially in section, of the control mechanism adapted to being manipulated by the patron when the seat is to be manipulated the same shows the 70 manipulating mechanism in inoperative position.

Fig. 7 is a side elevation, partially in section, of the mechanism illustrated in Fig. 6, but illustrates the same after the manipulation 75 of the same.

Fig. 8 is a cross section, side elevation, of the mechanism illustrated in Figs. 6 and 7, illustrating the same in conjunction with the stop mechanism for stopping the cycle of 80 operation when the cycle has been completed.

Fig. 9 is an inverted plan view of a seat section, taken on line 9—9 of Fig. 5, looking in the direction indicated; the same is made to illustrate the selective manipulative mechanism to be actuated by the key stem mechanism and illustrates the contact bars for starting the motor. 85

Fig. 10 is a longitudinal, side elevation, partially in section, illustrating the trip 90 mechanism to return the selective operating mechanism to normal position upon the completion of the cycle of operation.

Fig. 11 is a diagrammatical layout of the electric mechanism. 95

Fig. 12 is a cross section view, taken on line 12—12 of Fig. 8, looking in the direction indicated.

Like reference characters refer to like parts throughout the several views. 100

I preferably make my device selectively operative upon two sections of seats, each section here shown containing four seats, as illustrated in Fig. 1, but I do not wish to be limited to four seats in each section as any number of seats may be adapted to the mechanism illustrated. The seats are here shown with a vacant space in each section. The aisle is adjacent to seat 3. A platform 4 is provided for each section of seats having guide 105 110

ways 5, disposed in the platform. This platform may or may not be raised or be independent of the floor of the building, but is here described as a platform for convenience in description and illustration. Should the occupant of seat 6 in row A desire to leave his seat he would operate the selective manipulative key disposed adjacent and conveniently located at his seat and the first operation that would result would be a transfer of each of the seats disposed in row A toward the aisle the distance of one seat. Simultaneously with this movement each of the seats disposed in row B would be moved away from the aisle for the space of one seat. With this shifting of the seats thereafter a second operation would be set in motion wherein seats from row A would be shifted into row B at the aisle and seats from row B would be shifted into row A at the farthest point from the aisle, and seats would be transferred toward the aisle as shifted in row A and away from the aisle in row B until seat 6 would be delivered to the aisle position in row A at which time the selective mechanism would stop the cycle of operation. Should the occupant of seat 7, located in row B, desire to leave his seat; he would press the selective, manipulative key disposed at the seat and the following cycle of operation would be set in motion. First the aisle seat in row B and the seat farthest from the aisle in row would each be transferred to the opposite row A in the same section of two rows of seats, thereafter all seats in row B would be transferred toward the aisle and all seats in row A would be transferred away from the aisle and as each seat is transferred to the end of the row the same will then be transferred to the adjacent row until seat 7 is delivered to the aisle position at which time the cycle of operation is completed and the occupant will leave his seat. The mechanism necessary to effect this result will now be described in detail.

45 A prime mover 8, as an electric motor, is positioned central of the platform 4, and is disposed beneath the floor and is driven by electric current to be supplied from a source not here shown. A power shaft terminates each end of the shaft of the prime mover as here shown at 9 and 10, and for the purposes of speed reduction I have shown a worm mounted upon each of the shafts 9 and 10 and in working relation with a worm wheel disposed upon the related shafts 11 and 12. Two sets of drives are provided in connection with each of the shafts. One set is for driving a driven element, as chains 13 and 14, running longitudinally of the platform section for shifting the seats to and away from the aisle, and the other a driven element, as chains 17 and 18 for shifting the seats from the one row of seats to the adjacent row of seats. This is accomplished through the fact that the prime mover is adapted to be selectively driven, in

either direction. Each of the shafts 11 and 12 have a bevel gear disposed on their one end and are engaged with a like gear to deliver driving power to the shafts 15 and 16. Each of the shafts 15 and 16 are adapted to each drive a chain for the purpose of shifting the seats. The chains are shown at 17 and 18.

Leg and supporting elements are disposed beneath each seat and are adapted to engagement within the slots disposed in the platform for each series of seat sections. This arrangement is shown in Fig. 4 wherein the leg elements 19 are shown engaged within the slots which act as guideways for the seats. The legs are moved within the guideways through the action of the chains. A contact member 20 is disposed in the base of each seat, the same being shown in detail in Fig. 10, wherein the position of member 20 is substantially vertical and is maintained in that position through the action of a spring 21. The member 20 has a ball like bearing 22 disposed between its ends which is maintained in a working relation with supporting bearing members 22A placed thereabout. The member 22A is secured to the seat base 1. Projection 23 disposed upon the chain contacts with the member 20 on each of the driven chains and carries the seat in the direction the projection 23 is moving. If the seat is to be transferred to the oppositely disposed row, the same is then carried by the chain running in the opposite direction until delivery is made to the predetermined place.

The mechanism operating the movement of the seats is so arranged that during the movement of seats laterally there will be no movement of the seats transversely, and vice versa. Each of the chains 13, 14, 17 and 18 is provided with one projection 23, and are so arranged, that when the projection on the chains 13 and 14 engage a contact member 20 of a seat, the projection on each of the chains 17 and 18 will be out of engagement with a contact member; or if the projections on 17 and 18 engage, the projection on chains 13 and 14 will be out of position to engage the contact members. Chains 17 and 18 are longer than chains 13 and 14, and are therefore geared up at a higher rate of speed so that all the chains make a complete revolution in the same length of time. Although the contact member 20 is made somewhat flexible it will be retained in contact with the member 23 by the lower inner walls of the member 22A, as long as the member 23 is traveling in its upper horizontal path; but when the member 23 passes over the sprocket wheel to the lower position of the chain, the two members 20 and 23 will disengage; this permits the member 23 to engage the opposite side of the member 20 if a reversal of the movement of the chair is desired.

To provide for the chairs moving laterally to move as a unit, especially when one chair

only is in contact with a chain, I have provided on one side of the base plate 1, an overlapping portion 53, provided with an upwardly extending groove 54; upon the opposite side of each base is formed an upwardly extending flange or projection 55 that fits into the groove 54, this forms a locking device between two laterally adjacent seats. It will be seen that when a seat moves from one row to another its groove or projection will move out of engagement with the projection or groove of one chair, as the case may be, into engagement with the projection or groove of another chair.

15 The actuating key stem 24, placed at a convenient position at each seat is to be manually manipulated by the occupant of the seat and when so actuated completes the electric contact through the lever 25 secured to the lower end of the key stem completing the contact by the oppositely disposed end 25A of the lever to that engaged with the key stem engaging the wire 36. This electric current is of a low tension and only energizes the magnet 26.

20 The location of the seat determines in which direction the core of the magnet is to be manipulated. If the seat is disposed in row A at the time of the pressing of the key stem, the circuit will be completed through the electric conductors 27, and the other contact, and the seats will be moved toward the aisle in row A and away from the aisle in row B. Whereas if the seat is located in row B, the seats will move toward the aisle in row B and

25 away from the aisle in row A. The magnetizing of the magnet 26 draws the core in the direction indicated by the arrow and the core is locked in position as extended because of the pawl 28 engaging in the notch 29 of the core.

30 The drawing of the core 26A into locked position draws the rod 30 in the same direction. The switch elements 31 and 32 are directly secured to the rod 30 and the same closes the electric circuit connected with the motor by

35 the switch elements 31 and 32 engaging with the contact points 33 and 34. Thus driving the electric motor in one direction. When the magnet 35 is energized by the completion of the electric circuit through the connection

40 of end 25A of lever 25 with the conductor 27, the core of the magnet 35 will be drawn in the direction indicated by the arrow and the core will be locked by engagement with the pawl 37 locking the core by engagement with the notch 38, thus locking the same in position until released. As the core is drawn into locked position the switch elements 31 and 32 are made to engage with and complete the circuit through the conductor to the motor by

45 engaging the points 39 and 33 and thus rotating the motor in the opposite direction than when magnet 32 was energized. The switch elements 31 and 32 are normally maintained in balanced relationship and out of

50 contact through the action of the springs 40

and 41 returning the magnet cores to normal position after they have been released by the pawls 28 and 37. The magnets are mounted in pairs within a housing or casing 53A.

When the key stem 24 is actuated by the occupant of the seat the same actuates bell crank 42 journaled about supporting pin 43 by a projection 44, in fixed relation with the key stem engaging with the bell crank. The bell crank is normally maintained in position by the spring 45 engaging with the bell crank and the same in its normal position being disposed between the journal pin 43 and the end of the bell crank. When the bell crank is partially rotated about the supporting pin 43 in the direction indicated by the arrow in Fig. 8, until the point of contact of the spring 45 with the bell crank passes the vertical center line passing through the journal pin 43, the bell crank will be maintained in locked position by the action of the spring until released. A stand 47 is disposed in the aisle and adjacent each row of seat sections. To permit of an automatic stopping of the cycle when the seat occupied has reached the aisle location, referring to Fig. 8, the bell arm contacts with the stop lug 51 rotating the bell crank about pin 43, and raising its opposite end 42A against the arm 51A of key stem 48 thereby raising said key stem and releasing the magnet pawls. In the event an attendant, as an usher, should desire to stop the seat movement, all that is necessary is to manually actuate the key stem 48. The pressing of the push button 49 which is connected by the electric wiring 49A to one of the magnets energizes the magnet and will set in motion any desired section at any time by the attendant thus moving to or away from the aisle either row of seats since each row of seats has a stand and actuating mechanism. The push button connects the electric circuit with the electric motor and will continue to operate the same until the key stem 48 is actuated releasing the magnet pawls, thus throwing the switch and stopping the electric motor that acts as the prime mover for imparting movement to the seats.

I have provided elements through the actuation of which, either by the occupant of the seat from the seat, or by the actuation of the same by the attendant, or prospective occupant from an aisle location wherein the desired seat may be delivered to an aisle location.

To make the mechanism safe for use by the public I have provided a shield 52 that entirely covers all electric connections and other elements and protects the same from contact by outside influences.

While the form of mechanism herein shown and described is admirably adapted to fulfill the objects primarily stated, it is to be understood that it is not intended to confine the invention to the one form of embodiment

herein shown and described, as it is susceptible of embodiment in various forms, all coming within the scope of the claims which follow:

5. What I claim is:—

1. In a device of the class described, the combination of two rows of seats, there being an aisle common to each row, means adapted for moving the seats in a horizontal plane 10 whereby the position of all seats relative to the aisle changes, and other means operable from each seat adapted for controlling the last mentioned means.
2. In a device of the class described, the combination of horizontal guideways, parallel rows of seats movably carried upon said guideways, means for imparting movement to the aforesaid seats along said guideways, other means controlling the last mentioned 20 means, and means cooperating with and adapted to cause the last mentioned means to stop the movement of the seats when a pre-selected seat has moved to a predetermined position relative to the other seats.
3. In a device of the class described, the combination of seats arranged in rows, supporting legs associated with said seats, guideways for said supporting legs to determine the path of travel of the seats, power means 30 for imparting movement to each seat and selective means for determining the direction of travel of the seats and for predetermining the stopping location of the movement.
4. In a device of the class described, the combination of a group of seats arranged in rows, supporting elements for said seats, guideways for the supporting elements and power means for imparting movement to the 40 seats within the guideways to move the seats to or away from the aisle, or forward or backward to deliver a selected seat to a predetermined position for the seat selected.
5. In a device of the class described, the combination of a series of seats arranged in parallel rows, supporting elements for said seats, guideways associated with the supporting elements, power means disposed adjacent the guideways adapted to move the seats toward or away from the aisle, or to, or from alternate rows, and selective means for predetermining the direction of movement and for predetermining the point of stop of the seats when moved.
6. In a device of the class described, the combination of a group of seats arranged in rows, power means for horizontally shifting the seats relative to each other, means disposed adjacent each seat for causing the power means to impart movement to the seats, and other means to stop the seats when a predetermined one of the seats has moved to a predetermined point.
7. In a device of the class described, the combination of seats arranged in parallel 65 rows, power means for imparting horizontal movement to change the relative position of each of the seats, means for causing the power means to impart movement to the seats, and means cooperating with the last mentioned 70 means for predetermining the point of stop of the seats when moved.
8. In a device of the class described, the combination of a group of seats, power means for imparting horizontal movement to each 75 seat in the group, elements disposed at each seat for causing the power means to impart movement to each seat of the group, and elements cooperating with the last mentioned elements for predetermining the point of stop 80 of the seat from which the movement was initiated.
9. In a device of the class described, the combination of a group of seats, starting elements associated with each seat, power means 85 controlled by said starting elements associated with the group of seats for imparting movement to the seats in a predetermined horizontal pathway, and additional means disposed adjacent the aisle end of each row or 90 group for independently controlling the power means.
10. In a device of the class described, the combination of a group of seats arranged in rows, power means associated with the group 95 for imparting horizontal movement to each seat of the group, starting elements associated with each seat for causing the power means to impart movement to the group, and means 100 cooperating with the aforesaid starting elements disposed at the aisle end of each row of seats for independently causing the power means to impart movement to the group and for stopping the movement.
11. In a seat positioned device of the class 105 described, two rows of seats provided with a common aisle, means oppositely moving the said rows to and from the aisle to the extent of one seat, there being a gap in each row the width of an opposing seat in the other row; 110 means cooperating with the last mentioned means moving a seat of each row into the opposing gap of the other row, and means controlling the foregoing moving means.
12. In a seat positioning device, a plurality 115 of seats arranged in parallel rows, there being an entrance and exit station to said seats, means whereby a seat in one row remote from said entrance and exit station, moves toward said station, means whereby seats intermediate said seat and said station move one by one from the one row to the other, and means whereby a like number of seats move in like manner from the other row to the one row to 120 positions other than intermediate the first 125 mentioned seat and said entrance and exit station.

LEE OTIS THOMPSON.
